UNITED STATES PATENT OFFICE

2,192,045

ELECTRIC CIRCUIT BREAKER

Leonard J. Linde, Drexel Hill, Pa., assignor to
General Electric Company, a corporation of
New York

Application June 13, 1939, Serial No. 278,855

4 Claims. (Cl. 200—149)

My invention relates to electric circuit breakers, and more particularly to circuit breakers of the type wherein an arc-extinguishing gas is emitted by an arc-confining structure under the influence of the arc heat.

In breakers of this type it is desirable to provide for a large contact area between the arc and the walls of the arc-confining passage so that arc-extinguishing gas will be liberated in sufficient quantities to create a pressure that will extinguish the arc effectively, and it is an object of this invention to provide an improved circuit breaker construction which provides for an extended contact area between the arc and the gas-emitting material and results in a circuit breaker having a high current interrupting capacity for its physical size.

It is another object of this invention to provide an improved circuit breaker construction which is structurally strong, reliable in service and economical to manufacture.

Further objects and advantages of the invention will become apparent as the following description proceeds, reference being had to the drawing in which Fig. 1 is an elevational view in section of a circuit breaker embodying the invention, and Fig. 2 is a sectional view taken along the lines 2—2 of Fig. 1.

The circuit breaker illustrated in the drawing, by way of example, comprises an arc-confining structure designated generally by the numeral 10, a stationary contact 11 and a movable contact rod 12. The arc-confining structure illustrated is in the form of an elongated body of insulating material made up of a plurality of disks 13 which are assembled in a cylindrical housing 14 of insulating material. The disks may be stacked and secured together by suitable fastening means extending longitudinally therethrough, in which case the housing may be omitted if desired. At one end the structure is closed by a housing 15 of conducting material which may be secured to one end of the insulating cylinder 14 by any suitable means (not shown). Between the conducting housing and the upper disk of the arc-confining structure is positioned the stationary contact 11 which may be in the form of an annular segmental ring, in which the segments are resiliently bound together by an encircling helical spring 16.

The arc-confining structure is provided with an arc-confining passage 17 extending longitudinally therethrough for the reception of the movable contact rod. The passage 17 is of such curvilinear cross-section that a rib or pencil 18

extends longitudinally of the arc-confining structure and is supported from the side wall of the passage. In the illustrated embodiment, the arc-confining structure is formed from a plurality of disks having a curvilinear slot formed therein which are stacked and secured together in any suitable manner with the slots in alignment to provide the arc-confining passage. This structure is very easy to manufacture since the disks may be formed in the desired shape without any difficulty.

The hollow movable contact is provided with a longitudinal slot 19 of such width as to accommodate the rib 18 at the region where the rib connects with the body of the arc-confining structure. With the construction just described, it is apparent that the rib 18 is partially surrounded by the movable contact so that there is an extended area of contact between the walls of the arc-confining passage and movable contact. The rib or pencil 18 which lies within the movable contact is supported throughout its length from the side wall of the arc-confining passage and in the particular embodiment illustrated forms an integral part of the remainder of the arc-confining structure.

The insulating material which forms the arc-confining structure is of the type which emits arc-extinguishing gas under the influence of the arc heat and may be, for example, a suitable artificial resin or a hard fiber having this characteristic. It is not necessary that the entire structure be of gas-emitting material since it is possible to provide the arc-confining passage with a lining of material having this characteristic.

When heavy current arcs are drawn in the arc passage large quantities of gas are emitted from the walls thereof under the influence of the arc and in order to avoid excessive pressure within the arc passage in the illustrated embodiment suitable radial vents 20 are provided intermediate the ends of the arc passage. These vents may communicate with a muffler and expansion chamber (not shown) mounted concentrically with the arc-confining structure. Such a construction is shown and described in Patent No. 2,152,497, Petermichl, dated March 28, 1939.

In the operation of the circuit breaker above described the movable contact rod is moved downwardly from the position shown in Fig. 1 by a suitable operating mechanism (not shown) in response to a circuit condition to be controlled. Upon separation of the fixed and movable contacts an arc is drawn in the passage 17 which acts upon the gas-emitting material defining the

passage to liberate quantities of arc-extinguishing gas. As the rod 12 is withdrawn from the passage the vents 20 are opened and in the case of a heavy current arc such as exists under short circuit conditions sufficient gas will have been liberated to extinguish the arc at this point and the hot ionized gases are exhausted through the radial vents. If the arc is not extinguished at this point, the action of the arc on the gas-emitting material continues as the movable contact is withdrawn until the arc is extinguished before the movable contact reaches its lower limit of travel.

From the foregoing description it is seen that the invention provides a novel circuit breaker construction in which an extended area of contact is provided between the walls of an arc passage defined by material having gas-emitting properties under the influence of an electric arc. The improved structure provides for supporting the portion of the insulating material which lies within the movable contact from a side wall of the arc passage thereby eliminating additional supporting means and, at the same time, providing a structure which is easier to manufacture and more durable in use.

While I have shown and described a particular embodiment of my invention, modifications thereof will be apparent to those skilled in the art. I do not therefore desire my invention to be limited to the particular construction shown and described, and I intend in the appended claims to cover all modifications within the spirit and scope of my invention.

What I claim as new and desire to secure by Letters Patent of the United States is:

1. An electric circuit breaker comprising means for forming an elongated arc-confining passage, said passage being defined by insulating material adapted to emit an arc-extinguishing gas under the influence of an electric arc, a rib of insulating material extending longitudinally of said passage and supported from a side wall thereof, relatively movable contacts separable to form an arc in said passage, one of said contacts having

such cross-sectional configuration as to enclose partially said longitudinally extending rib.

2. An electric circuit breaker comprising a body of insulating material having an elongated arc-confining passage formed therein, a fixed contact, a movable contact separable from said fixed contact to draw an arc in said passage, said passage being defined by insulating material adapted to emit an arc-extinguishing gas under the influence of the arc heat, a rib of insulating material extending longitudinally of said passage and supported from a side wall thereof, said movable contact having a curvilinear cross-section such as to enclose partially said rib.

3. An electric circuit breaker comprising a body of insulating material having an arc-confining passage formed therein, a fixed contact, a movable contact separable from said fixed contact to form an arc in said passage, said passage being defined by insulating material adapted to emit an arc-extinguishing gas under the influence of arc heat, said body of insulating material having an integral portion extending into said passage and longitudinally thereof, said movable contact having such a cross-sectional configuration as to enclose said integral portion extending into said passage in the closed circuit position of said circuit breaker.

4. An electric circuit breaker comprising means forming an elongated arc-confining passage, a fixed contact, a hollow movable contact separable from said fixed contact to form an arc in said passage, said passage being defined by insulating material adapted to emit an arc-extinguishing gas under the influence of the arc heat, and a rib of insulating material formed integrally with a side wall of said arc-confining passage and extending longitudinally thereof, said movable contact having an elongated slot therein for receiving said rib in the region of connection with the side wall whereby said rib lies within said hollow movable contact when the circuit breaker is in its closed position.

LEONARD J. LINDE.
